(57) **CLAIM**

The ornamental design for a cap, as shown and described.

DESCRIPTION

FIG. 1 is a top perspective view of a cap showing our new design;

FIG. 2 is a bottom perspective view thereof;

FIG. 3 is a first side elevation view thereof;

FIG. 4 is a second side elevation view thereof;

FIG. 5 is a third side elevation view thereof;

FIG. 6 is a fourth side elevation view thereof;

FIG. 7 is a top plan view thereof;

FIG. 8 is a bottom plan view thereof;

FIG. 9 is another top perspective view of the cap, shown in a position of use with an exemplary container; and,

FIG. 10 is an exploded perspective view thereof.

The broken lines are shown for the purpose of illustrating environmental subject matter of an exemplary container and form no part of the claimed design.

1 Claim, 7 Drawing Sheets
